[57] **CLAIM**

The ornamental design for a surgical gown and hood, as shown and described.

DESCRIPTION

FIG. 1 is a perspective view of a surgical gown and hood showing my new design;

FIG. 2 is a front elevational view thereof;

FIG. 3 is a side elevational view thereof taken from the right as viewed in FIG. 2;

FIG. 4 is a rear elevational view thereof;

FIG. 5 is a top plan view thereof;

FIG. 6 is a bottom plan view thereof;

FIG. 7 is a view of an alternative embodiment thereof showing a hood cover in place;

FIG. 8 is a front elevational view of the embodiment of FIG. 7;

FIG. 9 is a side elevational view of the embodiment of FIG. 7 taken from the right as viewed in FIG. 8;

FIG. 10 is a rear elevational view of the embodiment of FIG. 7;

FIG. 11 is a top plan view of the embodiment of FIG. 7; and,

FIG. 12 is a bottom plan view of the embodiment of FIG. 7. The broken line showing of a man's head, hands, feet, and interior of the hood, is for illustrative purposes only and forms no part of the claimed design.
